UNITED STATES PATENT OFFICE.

NORMAN LIPSKY, OF NEW YORK, N. Y., ASSIGNOR TO HALCOLITE COMPANY, INC.,
A CORPORATION OF NEW YORK.

DESIGN FOR A LIGHTING-FIXTURE WALL BRACKET OR ANALOGOUS ARTICLE.

Application filed February 21, 1928. Serial No. 25,530. Term of patent 7 years.

To all whom it may concern:

Be it known that I, NORMAN LIPSKY, a citizen of the United States of America, and a resident of the city, county, and State of New York, have invented a new, original, and ornamental Design for a Lighting-Fixture Wall Bracket or Analogous Article, of which the following is a specification, reference being had to the accompanying drawing, forming a part hereof.

In this drawing:

Figure 1 is a front elevational view of the lighting fixture wall bracket or analogous article; and

Figure 2 is a diagrammatic top outline view of the same.

I claim:

The ornamental design for a lighting fixture wall bracket or analogous article substantially as shown.

NORMAN LIPSKY.
